2 Sheets-Sheet 2

UNITED STATES PATENT OFFICE.

EZRA B. SMITH, OF CHICAGO, ILLINOIS, ASSIGNOR TO THE J. G. WILSON CORPORATION, OF NEW YORK, N. Y., A CORPORATION OF VIRGINIA.

GUIDE MEANS FOR SLIDING DOORS.

Application filed June 5, 1924. Serial No. 717,954.

This invention relates to sliding doors and particularly to that type of door which is adapted to be moved by a simultaneous sliding and rotating motion into an open position which is substantially at right angles to its closed position.

Such doors, sometimes called "disappearing doors", are particularly useful in connection with structures where it is desirable that the door may be moved to a position along the side of the structure through a minimum amount of space: For example, such doors are exceedingly well adapted for use in wardrobes, booths, washrooms, and similar enclosures and also in garages and like structures in which an economical use of the space inside the enclosure is often essential, and which, moreover, are frequently so situated that it is desirable that the doors project outwardly a minimum distance during their movement. In the case of wardrobes, for instance, and other structures inside of buildings, doors which project much beyond the face of the wardrobe are likely to obstruct the passageway on which the wardrobe faces and when such structures are used in public buildings such a projection across a passageway is not only a source of great inconvenience but increases the fire hazard. In the case of structures placed in the open air, the further the doors project outwardly the greater will be the likelihood that the wind will retard their movement or strain their attachments and the greater the interference to their movement from snow and ice.

An objection to the general use of doors which may be simultaneously slid and rotated to a position alongside of the structure, however, has been that the mounting and guiding means therefor, heretofore known and of such a nature that there is a tendency for the doors equipped therewith to sway or to stick during their movement. It is important that the movement of such doors be easy, smooth and substantially frictionless, that the doors be stabilized during such movement, and that the means for stabilizing the doors be sturdy, and that it be smooth and noiseless in operation, and that its operation will not retard or obstruct the movement of the door.

An important object of this invention is, therefore, to provide sturdy guide means

which will operate to guide a door from a closed position to an open position substantially at right angles thereto in a steady, smooth, easy, and substantially frictionless manner.

Another important object of the invention is to provide stabilizing means in connection with said guide means whereby any swaying or oscillating movement of the door may be effectively prevented without impairing the freedom of the opening or closing movements of the door.

It is another object of the invention to provide means in connection with such stabilizing means by which the noise of operation will be reduced to a minimum.

In order that a door of this type may be moved in an easy and frictionless manner and that the stabilizing means operate correctly, it is necessary properly to adjust the relative vertical positions of the door and its guide tracks and it is also desirable that such adjustments may be readily made from time to time to allow for sagging of the door or its associated parts. It is, therefore, another object of the invention to provide means whereby the relative vertical positions of the door and its guide tracks may be readily adjusted.

In connection with doors which are simultaneously slid and rotated in the manner described, it is sometimes desirable to provide a bottom guide for the door consisting of a groove in the floor over which the door moves and a stud projecting from the door into the groove. This arrangement, however, is likely to prove unsatisfactory because of a tendency for dirt to collect in the groove and to obstruct the movement of the door, often effectively preventing the movement of the door as the stud approaches the end of the groove. Another object of the invention is to provide a lower guide means of this type which will be self-cleaning.

Other objects of the invention, together with the important features thereof, will be apparent from the following description taken in connection with the accompanying drawings which illustrate the invention as embodied in connection with a pair of slideable doors normally closing the face of the wardrobe. It should be understood however that the invention is by no means limited to

such an embodiment, but is adapted for use on doors, windows, or the like having a movement of the type outlined above and used in connection with a structure of any sort.

In the drawings, Fig. 1 is a front view of a wardrobe having doors equipped with guiding and stabilizing means embodying the features of the invention;

10 Fig. 2 is a section through the line 2—2 in Fig. 1, illustrating particularly the means for slidably and rotatably supporting the door and the means for guiding one edge of the door and for stabilizing the door adjustably.

15 Fig. 3 is a section through the line 3—3 in Fig. 1, illustrating particularly the groove whereby the bottom of the door is guided;

20 Fig. 4 is a side view of one of the doors showing in detail the supporting means and the lower guide means therefor;

25 Fig. 5 is a front view of the supporting means;

30 Fig. 6 is a top view, partly in section, showing in detail the guiding and stabilizing device;

35 Fig. 7 is a front view of this device from line 7—7 in Fig. 6; and

40 Fig. 8 is an end view thereof from the line 8—8 in Fig. 6.

45 The drawings show a wardrobe closed by a pair of doors equipped with supporting, guiding, and stabilizing means which cooperate to control the movement of the doors so that they can be slid with an easy, steady motion from their closed position across the front of the wardrobe to an open position along the sides thereof. The dotted lines in Fig. 2 indicate the maximum extent outwardly and inwardly of the path of movement of the door 20. The dotted lines in Fig. 3 indicate a position of the door 20 intermediate its open and closed positions showing how it extends between the lintel and the threshold of the doorway. This showing, taken in connection with the following description, will make clear the desirability of providing the door with a stabilizer which is certain and sure in operation and which will, besides its other functions prevent the door from sticking against the lintel or the threshold. These doors, moreover, require for their movement a minimum amount of unobstructed space inside and outside of the wardrobe.

50 Figs. 1, 2 and 3 show a wardrobe 10 comprising a base 12, sides 13 and 14 and a top 16. The front of the wardrobe is open to form a doorway which a pair of doors 19 and 20 are adapted to close. In the wardrobe there may be provided one or more shelves 21, hooks 22, umbrella racks 23, drip pans 24 and other necessary or desirable holders for clothes or other articles. These 55 may extend throughout the greater part of

the space inside the wardrobe because of the small amount of space required for the movement of the doors.

60 In the particular embodiment of the invention shown in the drawings the door 19 is supported on a track 25 running obliquely from the lintel 26 of the doorway to an inward position near the top of the side 13 of the wardrobe by means of a hanger 28 comprising preferably a roller bearing sheave 30 65 turning on a shaft 31 held by the sides of a saddle 32 extending under the track. The saddle 32 is rotatably mounted on an attachment 33 on the door by means of a threaded pin 34 extending through an opening in lug 35 on the attachment. A pair of nuts 36 are provided on pin 34 whereby the height of the door may be adjusted and the door locked in its adjusted position.

70 A guide track 40 is attached to the side 13 near its vertical center and is set outwardly therefrom by a spacing member 41 which may be biased slightly in the manner shown, so as to permit the door to bear against the inside of its jamb when closed 75 and yet to be in a position substantially perpendicular to its doorway when opened. This track, in the embodiment shown, is made vertically adjustable upon a spacing member 41 by the provision therein of the 80

vertical slots 42 in which are inserted screws 43 to hold it in place. In order to guide the outward edge 19' of the door 19 along track 40 so as to cause the rotation of the door as its hanger slides along track 25 and so as to stabilize the door to prevent it from swaying on its hanger and to prevent any vertical movement of either edge of the door such as would tend to interfere with its smooth operation, there is provided a guiding and stabilizing means movable along track 40 which in the embodiment shown comprises a plate 44 affixed near the vertical center of the edge 19' of the door, and a plate 45 which is hinged to plate 44 and on which are fixedly mounted a pair of shafts 46 extending over track 40 and a pair of shafts 47 extending under track 40. On each of shafts 46 is a sheave 48 adapted to roll along the top of track 40 and on each of shafts 47 is a sheave 49 adapted to roll along the bottom of the track. As the shaft of each of these four sheaves is securely fastened to plate 45, and as two of these sheaves are set against either side of the track 40, it will be seen that there 110

115 is provided a stabilizing means which will effectively prevent any swaying of the door, and yet will in no way oppose or retard the opening and closing movements thereof even if pressure is applied thereto tending to cause a vertical movement of either of its edges. In other words, such vertical movement is effectively prevented by this stabilizing means without obstructing the normal operation of the door. For example, if someone 120

hangs on or leans against the door while opening or closing it, the stabilizing device will prevent the door from being swayed so as to stick against any adjacent members, 5 such as the threshold or the lintel of the doorway, and will at the same time permit a free opening or closing movement. It is sometimes desirable to provide means to prevent rattling of the stabilizing means. Such 10 an anti-rattling means is shown in the drawing, and consists of a spring 53 spiraled about the pin 54 of the hinge joining plates 44 and 45 and extending along the inner surfaces of these plates so as to tend to spread 15 them apart, thus causing the inner flanges of the sheaves to bear firmly against track 40 at all times.

In order to insure a smooth and steady operation of the door, it is well to provide a 20 guide means for the bottom thereof. In the drawing this means is shown as a groove 55 in the base 12 of the wardrobe, in which groove moves a stud 58 which is attached by means of a bracket 59 to the bottom of the 25 door 19. In order that dust and dirt collected by the groove 55 may not obstruct the movement of the door the groove is extended to the edges of the base so that the movement of the stud 58 along the groove will tend to 30 push out of its open ends any dust or dirt collected by the groove. In case the floor over which the door moves and in which the groove 55 is placed extends a long distance outwardly from the position through which 35 the door moves, or in case the sides 13 are unusually thick, means consisting of two or more holes bored through the floor from groove 55 may be provided in order that the groove may be cleaned by the movement of 40 the stud 58 therein.

The supporting, guiding, and stabilizing means used in connection with door 20 are similar to those used in connection with door 19 and have been indicated in the drawings 45 by similar reference numerals.

For the sake of convenience, the term "door" is used herein to include any member which may be slid from a position in which it closes or partially closes an opening, to another position substantially perpendicular thereto by the aid of supporting, guiding, and stabilizing means such as contemplated by this invention.

The invention, moreover, is in no way restricted to the particular embodiment thereof shown, but only by the scope of the appended claims.

I claim:

1. A structure having a doorway, a door 60 mounted for combined sliding and swinging movement, a track for guiding the door across the doorway, a hanger for supporting the door at its upper edge slidably mounted

on the track, a pivot for the door carried by said hanger and slidable with the door, a 65 second pivot for the door arranged at the base thereof and in substantially vertical alignment with said first pivot and slid- able with the door, means for guiding said last pivot, and means for guiding a part of 70 the door at one side of its pivotal point in a direction transverse to the plane of the doorway.

2. A structure provided with a doorway and side walls extending rearwardly there- 75 from, a jamb at one side of said doorway, a door mounted for combined sliding and swinging movement between a position across the doorway and inside the jamb and a position alongside a side wall, means for 80 guiding a point in the door in a direction across the doorway, means for guiding a side marginal portion of the door in a di- 85 rection transverse to the plane of the doorway comprising track engaging means at- tached to said side marginal portion of the door, and a track for guiding said track 90 engaging means located along a side wall and inclined outwardly away from said wall in a direction from the front toward the rear of said wall to cause the door to close within the jamb and to locate the door sub- stantially parallel with the side wall when open.

3. A structure provided with a doorway, a 95 door mounted for combined sliding and swinging movement from a position across the doorway to a position substantially per- 100 pendicular to the plane of the doorway, piv- ots for the door slidable with the door and arranged in substantially vertical alignment, parallel tracks for guiding the upper and lower margins of the door, and means for guiding a side margin of the door.

4. A structure provided with a door and 105 side walls extending rearwardly therefrom, a door mounted for combined sliding and swinging movement between a position across the doorway and a position along- 110 side a side wall, means for guiding the door in a direction across the doorway, means for guiding a side marginal portion of the door in a direction transverse to the doorway, comprising track engaging means attached 115 to said side marginal portion of the door, a track engaged by said track engaging means, located along a side wall and in- clined outwardly from said wall in a direc- 120 tion from the front toward the rear of said wall to cause the door to close into a posi- tion with its side margin relatively close to the side wall and to be located substantially parallel with the side wall when open.

Signed at New York city this 3rd day of June, 1924.

EZRA B. SMITH.
